UNITED STATES PATENT OFFICE.

GIDEON EFRAIM SANDELOM, OF GOTTEBORG, SWEDEN.

ROTATORY BRUSH OR SCRAPER FOR REMOVING RUST, PAINT, OR THE LIKE.

1,414,305.

Specification of Letters Patent. Patented Apr. 25, 1922.

Application filed December 3, 1920. Serial No. 428,158.

To all whom it may concern:

Be it known that I, GIDEON EFRAIM SANDELOM, a subject of the King of Sweden, residing at Gottenborg, Sweden, have invented 5 certain new and useful Improvements in Rotatory Brushes or Scrapers for Removing Rust, Paint, or the like, of which the following is a specification.

The present invention has for its object 10 to provide an improved rotatory brush or scraper for the class of work mentioned, by which the disadvantages just mentioned are overcome. The invention is chiefly characterized therein, that the operative surfaces 15 of all the single bristles or scrapers are positioned in practically a common plane, perpendicular to the axis of rotation of the tool.

In the accompanying drawing an embodiment of the invention is illustrated. Fig. 1 20 shows a perspective view of the improved tool and Fig. 2 partly in section an elevation of the same tool on a reduced scale and provided upon a driving shaft with a holder.

Similar letters refer to corresponding 25 parts all through the drawing.

In the drawing 1 denotes a circular base plate, which is provided with two axially directed lugs 2 diametrically opposed to each other, a shaft 3 being journalled in the said 30 lugs and retained in its proper position by means of a head 4 provided on one end of the shaft and a split pin 5 going through the opposite end of the said shaft. On the shaft 3 there is provided a plurality of 35 bristles 6 comprising each a yielding member as for instance a steel wire, the medial portion of which is wound in the shape of a spiral coil 7, surrounding the shaft 3 with the one end of the spiral coil extended to 40 form the bristle 6 proper and the rear end 9 straightened and inserted into a hole 8 in the base plate 1. In this manner the coils 7 with the bristles 6 are prevented from being rotated about and displaced along the 45 shaft 3. The bristles 6 are shaped in such a way, that the operative square cut ends 10 of the bristles lie in a plane which is practically parallel to the base plate or at right angles to the axis of rotation of 50 the tool, and the intermediate portion of each bristle between the operative end 10 and the coil 7 is nearly parallel to the base plate and tangentially to a circle imagined as drawn with the centre on the axis of rotation of the base plate, whereby said middle 55 portion of all the bristles 6 are parallel to

one another projecting at right angles to the shaft 3.

The operative ends 10 of all the bristles are positioned in practically the same plane 60 as mentioned above, and the bristle ends are somewhat flattened so as to expose a larger width in their moving direction.

According to Fig. 2 the plate 1 by means of a threaded bolt 11 and nuts 12 and 13 is 65 attached to the end of a shaft 14, provided to be rotated in any suitable way (not shown). On bushings or bearings 15 provided on the shaft 14 there is rotatably mounted a socket 16 to serve as a grip or 70 holder for handling the tool.

The improved implement operates in the following manner:

The tool is held by the handle 16 and the yielding bristles 6 are pressed against the 75 surface 17 to be cleansed with the shaft 14 as nearly as possible perpendicular to the said surface. During the operation the operative surfaces 10 of the bristles accordingly describe circles upon the surface 17, 80 and by moving the tool in different directions each particular spot of the said surface will be treated from different sides, whereby the cleaning effect will be very intense. As all the bristles 6 during the whole 85 work always touch the surface to be cleansed, they will not be subjected to injurious blows thereupon and consequently the wear and tear of the bristles will be reduced to a minimum. The yielding effect 90 of the bristles allows the tool to be pressed evenly to the surface 17 notwithstanding some slight difference in the shape and length of the single members 6.

When the bristles have been torn so much, 95 that they cannot longer be used with advantage the pin 5 is removed, and the shaft 3 withdrawn from the lugs 2, whereby the bristles 6 are simultaneously disengaged. The tool will now be supplied with new 100 bristles simply by inserting the straight end portions 9 of the new coils 7 into the holes 8 and thereafter replacing the shaft through said coils successively.

The embodiment described and shown is 105 illustrated to be used principally as a brush. It is however, obvious that the relatively thin bristles shown can be substituted by bristles of a larger width and the tool then with greater advantages be employed as a 110 scraper.

I do not want to limit myself to the de-

tails of my improved device as shown and described, which can be varied without interfering with the scope of the invention.

Having thus described and ascertained my 5 invention, what I claim as new and want to secure by Letters Patent is:

1. A rotary tool for removing rust, paint and the like coatings from structures comprising a rotary shaft, and a plurality of 10 metallic bristles mounted on said shaft, a portion of each bristle extending at a slight inclination to the plane perpendicular to the axis of rotation of the shaft and having the operative end portion thereof disposed substantially 15 parallel to said axis, the several bristles having square cut operative end surfaces lying in a plane perpendicular to the axis of said shaft.
2. A rotatory tool of the class mentioned 20 comprising a rotatory shaft, a plurality of resilient wire bristles carried by said shaft and having square cut operative end surfaces disposed in a plane perpendicular to the axis of rotation of the tool, said wire 25 bristles having their opposite ends fixed in relation to the rotatory shaft and their medial portions rigidly supported so as to increase the springing effect of said bristles.
3. A rotary tool of the class described 30 comprising a rotary shaft, a plurality of

yielding wire bristles with square cut operative front end surfaces, the rear ends of the bristles engaging with said rotary shaft so as to hold the bristles yieldingly in place, the middle portions of said bristles being 35 coiled, and means to hold said coiled portions in place relative to the said rotary shaft.

4. A rotary tool of the character described comprising a rotary shaft, a base plate carried by said shaft, a second shaft journaled upon said base plate and arranged at right angles to the rotary shaft, a plurality of wire bristles having coiled portions embracing the second mentioned shaft, the operative ends of said wire bristles being square cut and lying in a plane perpendicular to the axis of rotation of the rotary shaft, the opposite ends of said wire bristles being 40 fixed to said base plate, and the portions of 45 said bristles lying intermediate the coiled portions and the operative ends lying tangentially with respect to the imaginary circular plane concentric to the axis of rotation of the rotary shaft and touching the plane 50 of the bristles.

In testimony whereof I have affixed my signature.

GIDEON EFRAIM SANDBLOM.
